UNITED STATES PATENT OFFICE.

GOTTFRIED WIRRER, OF PLAINFIELD, NEW JERSEY, ASSIGNOR TO INTERNATIONAL MOTOR COMPANY, OF NEW YORK, N. Y., A CORPORATION OF DELAWARE.

GRINDING WHEEL AND METHOD OF GRINDING.

Application filed June 13, 1922. Serial No. 567,993.

This invention relates to an improved wheel for grinding interrupted surfaces of cylindrical parts and to a method of grinding which is based essentially on a new principle. The general object of the invention is to provide a grinding wheel and method of grinding in which the wheel shall always be maintained in correct relation to the work and allow a great number of redressings or truings without altering the shape of the grinding face. Heretofore, it is the practice to provide a grinding wheel which is of such form as to involve its movement in a direction parallel to the axis of the grinding wheel. The method of grinding thus employed requires the use of relatively thin wheels, especially in cases where the interruptions are narrow and is one, consequently, which affords a very short life of the wheel. The amount of stock in known wheels available for trimming without altering the form of the wheel is so limited as to require constant replacement of the entire grinding element. The principal object of the present invention is to provide a grinding wheel which shall always afford, during its life, a relatively great bulk of stock for dressing or truing without altering the form of the wheel or changing the relation of the grinding face to the work. Another object is to provide an improved method of grinding in which the wheel shall be so mounted as to move in such relation to the work as to result in uniform wear on the grinding face while preserving always the proper relation between such grinding face and the work. More particularly, the improved wheel is one in which the grinding portion is formed as a truncated cone whose grinding edge is substantially at right angles to the pressure line of the element being ground. The improved method, in the particular application thereof to be hereinafter described, contemplates the feeding in of the grinding face to the work along a line parallel to the cone face to the end that no matter how much the wheel has been cut off in trimming or dressing the cutting face will always be presented in proper relation to the work. In accordance with the preferred embodiment of the invention a wheel having the characteristics indicated above is mounted on a rotatable spindle which may itself be moved bodily in a direction parallel to the cone face. In the grinding of interrupted surfaces, such as gear teeth, which involves the introduction of the grinding element into a comparatively narrow space, it has been desirable in practice to form the improved grinding lip with its grinding face at right angles to the spindle and at such an angle as will permit its introduction into such space in the element being ground, such as a gear tooth. In such a case the inside face of the grinding lip will be formed at the same angle so that the grinding face will always be of substantially the same form and dimensions during its entire life. It will be understood as the description proceeds that the invention is not to be limited to all of the matters of shape and size to be referred to hereinafter nor to the use to which the improved wheel is to be put but there has been selected for the purposes of this application embodiments of the improvements which are suitable for practical work in the grinding of gear teeth or rack teeth. In the drawings: Figure 1 is a view in plan of an improved grinding wheel so mounted as to permit the practice of the improved method when employed for the grinding of gear teeth. Figure 2 is a view in-end elevation of a portion of the parts shown in Figure 1. Figure 3 is a schematic view showing the relation of the cutting face of an improved wheel to the teeth of a rack where the spaces are deep and narrow. Figure 4 shows the wheel illustrated in Figure 3 after repeated dressings or trimmings. The drawings are intended to be somewhat diagrammatic in character it being unnecessary for an understanding of the invention to emphasize any of the details of construction of the machine on which the improved wheel may be mounted in such a manner as to practice the improved method. As shown in Figure 1 the wheel a is so far as concerns the grinding element carries, or has formed integral therewith, a generally conical grinding lip a' . The outer face a^2 of the grinding element is preferably formed parallel to the inner face a^3 and the inclination and thickness of the grinding element a' are such as to permit the grinding face a^4 thereof to be moved into the desired relation with the face of the tooth c and without interference by the adjacent

55 60 65 70 75 80 85 90 95 100 105 110

tooth *d*, when the grinding element is fed against the work along a line parallel to the cone face. If the lip were made circular rather than conical it is evident that its outer face would engage the element to be ground, as at the bottom of a tooth when the grinding edge was moved to the base of the tooth. This is objectionable and would limit the usefulness of the wheel. In so far as concerns the physical structure of the grinding wheel itself it is evident that the element *a'*, of grinding material, may be mounted on a carrier body of any desired form and material although in the illustrated embodiments it is proposed, in accordance with good manufacturing practice, to form the lip *a'* integral with a disk of the same material, such as carborundum. The wear on the grinding element, in any case, is on the grinding face *a'* which is the only part of the element which engages the surface of the work. This grinding face with its sharp edge may be moved to the base of a tooth and the angularity of the outer edge of the lip will prevent contact thereof with the bottom or other part of the work to be ground. This face is formed at right angles to the axis of the wheel *a* so that, as illustrated in Figure 1, its angle *e* with respect to the faces *a²*, *a³*, of the lip *a'* is complementary to the angle *b*.

The improved method of grinding has to do with the relation maintained between the grinding face *a'* and the face of the work so as to insure uniform wear on the face and adapt it at all times for ready trimming or dressing by means of an element which may be mounted in such relation thereto as to facilitate the trimming. As indicated hereinbefore, the invention is not to be limited to the details of construction of the elements employed for mounting the grinding element *a'* so as to practice the improved method and for that reason such elements are shown in diagrammatic form in the accompanying drawings.

The wheel *a*, as illustrated, may be mounted on a spindle *f* which carries driving pulleys *f'* whereby rotative movement is imparted to the spindle and wheel from any available source of power, and the spindle is journaled in suitable bearings *g*, *g'*, carried on a plate *h* which is, in turn, supported on a slide *i*. The slide *i* is mounted to travel in under-cut ways *k* formed in the supporting table *l* for the machine. The plate *h* may be adjusted angularly on the slide *i* and set in any desired angular position thereon by means of bolts *i'* the reason for this adjustment being pointed out more particularly hereinafter in connection with the description of the improved method of operation. Further adjustment may be effected by swiveling the base *h* on the table *l* so that it may be swung angularly for the

purpose of bringing the grinding face *a'* of the wheel at right angles to the pressure line of the work to be ground. The line of travel of the slide *i* is indicated by the center line *i'* in Figure 1. The axis of rotation *f* of the grinding element *a'* is indicated by the center line *f'* of the spindle *f*. The lines *A²* and *A³* are prolongations of the outer and inner faces *a²*, *a³*, respectively, of the grinding element extended to intersect the axis *f'*. These lines *A²*, *A³*, in the preferred form, are parallel and are parallel to the cone face which, for the purposes of the description may be considered as the line *A²*. It appears clearly from Figure 1 that the cone face *A²* is parallel to the line *i'* which indicates the direction of travel of the slide *i*.

In setting up the wheel for a grinding operation the base *h* will be set in such angular relation as to present the face *a'* properly to the work, i. e. preferably at right angles to the pressure line. Since a different wheel will be provided, generally speaking, for the grinding of different work, depending upon the pressure angle, the angular position of the base *h* will be changed for each different wheel so as to maintain the angular relations described herein. For feeding in the wheel properly for any given pressure angle, the plate *h* will be adjusted angularly on the slide *i* so that the slide will move parallel.

In operation, with the parts set in the relations described the face *a'* of the grinding element *a'* will be moved into grinding engagement with the face of the tooth *c* by movement of the slide *i* along the line of travel *i'* which is parallel to the cone face *A²*. When the gear is rolled on its axis to present different portions of the tooth *c* to the face *a'* the same relation of parts will be maintained and wear on the grinding element *a'* will take place uniformly and steadily over the grinding face *a'* and from the outer edge *a²* to the inner edge *a³* of the grinding element. The bulk of unused grinding material in the lip *a'* is measured by the depth of the lip. Repeated dressings thereof will find an effective grinding face presented of such form and dimensions as were originally provided. It is evident, of course, that the dimensions of the grinding element *a'* and its angularity when fed against the tooth *c* along a line of travel indicated at *i'* must be such as to enable its outer edge *a²* to clear the adjacent tooth *d* while enabling the ground tooth *c* to be engaged by the grinding face *a'* clear to its base. In each of these figures the cone face is indicated at *A²* and the line of travel of the grinding element at *i'*, these two lines being parallel. The angular relations described with respect to the wheel in Figure 1 are maintained as regards the axis of rota-

tion, the cone face and the line of travel of the supporting slide, all being fixed in conformity to the pressure angle of the work being ground. Figure 4 shows the wheel 5 illustrated in Figure 3 after repeated trimmings of the grinding lip and shows in the last view the limitation of its usefulness wherein the lip has been completely trimmed away and the grinding material lies in the 10 plane of the disk. In each successive trimming the form of the grinding face is preserved and is maintained in a plane at right angles to the axis of rotation.

While the present invention is not to be 15 limited to the character of the trimming mechanism employed there has been shown one convenient form which permits the trimming to be carried on without changing the relation of the angles initially set up for 20 practice of the grinding method in accordance with the description hereinbefore given. The table *l* may have mounted pivotally thereon as on a bracket *l'* a swinging bell-crank *m* in one arm of which is maintained a diamond *m'* and on the other arm of which may be formed a convenient hand-grip to facilitate rocking of the bell-crank on its pivotal support. The supporting bracket *l'* may be rotatably adjusted and secured in any desired angular position by 25 suitable adjusting devices illustrated as a locking bolt *l''*. By revolving the bracket *l'* about its pivotal support the bell-crank *m* may be brought into parallelism with the 30 grinding face *a'* of the grinding element *a*. The axis of the diamond *m'* is at right angles to the face *a'*. With the parts in this position movement of the slide *i* will bring the 35 working face *a'* into the plane of the diamond and rocking of the bell-crank *m* will swing the diamond across the face meanwhile trimming it flat and in a plane which is at right angles to the axis of rotation, as is desired. This simple trimming operation 40 may be carried on as desired without disturbing the relationship between the elements employed in the mounting of the grinding parts and enables the diamond *m'* to be moved out of interfering relation with 45 the grinding elements *a'* when desired. This 50

movement, indeed, may be facilitated by mounting the table *l* on a slide as indicated at *l''* so that all of the parts thereon may be moved towards and away from the fixed bracket *l'* as by manipulation of a hand-wheel *l''*, in a manner commonly practised.

As indicated hereinbefore, the invention is not to be limited to details of construction of any of the parts illustrated or described nor to the character of the trimming mechanism, since in its broader aspects the invention is concerned with the provision of a grinding wheel and a method of grinding wherein the stated objects are realized by maintaining, in general, the relation of parts 60 described.

What I claim is:

1. A grinding element of generally conical form having a grinding face at its end, means to support the grinding element rotatably in grinding relation to the work and means to feed the grinding element into the work along a line parallel to the cone face. 70
2. A grinding element of generally conical form in which the cone angle is such as to permit the element to clear the work to be ground, a spindle on which the grinding element is rotatably mounted, and a slide on which the spindle is mounted movable at an angle to the axis of the spindle equal to the angle between the cone face and its axis. 75
3. In combination, a grinding element of generally conical form having a grinding face on its end, a spindle on which the grinding element is rotatably mounted, a slide on which the spindle is supported, means to adjust the slide angularly to bring the grinding face in predetermined relation to the work to be ground, and means to adjust the angle of the spindle with respect to the slide whereby the line of feed of the grinding element into the work may be adjusted. 85
4. The herein described method of grinding which consists in applying a grinding wheel to the work to be ground, moving the faces thereof relatively and feeding in the wheel along a line parallel to the cone face. 90

This specification signed this 23rd day of May, A. D. 1922.
